ELECTRIC SWITCH AND SWITCH
OPERATING MECHANISM

Carl A. Christofferson, Acton, Mass., assignor to
The Chase-Shawmut Company, Newburyport,
Mass., a corporation of Massachusetts

Application June 8, 1942, Serial No. 446,170

10 Claims. (Cl. 200—116)

The present invention relates to circuit breakers and, as illustrated herein, relates more particularly to a combined switch and circuit breaker, and especially the operating mechanism for the circuit controlling conductors thereof, of the type wherein the breaker will open in response to abnormal current conditions but when desired may be maintained manually in circuit closed position even though the abnormal current condition persists.

There is need for a small combined switch and circuit breaker that can be opened and closed manually, that can open automatically in response to overload in the circuit and that can be maintained closed in spite of the overload, at least for a period of time sufficient for the overloaded circuit to accomplish its intended purpose.

Such a circuit control and protective device and the operating mechanism for the circuit-controlling contacts constitutes an object of this invention.

A further object of the invention is the provision of a switch and circuit breaker as above set forth wherein the circuit is closed and also opened rapidly, as with a snap action, by the use of an over-center spring.

Another object of the invention is the provision of an improved switch and circuit breaker, and the operating mechanism for the circuit-controlling contacts thereof, wherein the contacts are caused to separate in response to an overload and the mechanism is reset and the contacts restored into engagement by movement of the operating handle from a position corresponding to the open position of the circuit to a position corresponding to the closed position of the circuit.

A yet further object of the invention is the provision of an improved switch and circuit breaker wherein the operating handle is supported by a swinging member normally held from swinging by current responsive means and, when released, swings in a manner to effect its own movement and movement of the movable contact member of the switch into positions corresponding to open circuit positions, the mechanism being so arranged that such movement is prevented when the handle is held manually in its closed circuit position, and the swinging lever being reset and the circuit being reclosed by manual movement of the handle into its closed-circuit position.

Another object of the invention is to provide a combined switch and circuit breaker which can be automatically reset whenever the operating

handle therefor is moved into circuit closed position and will remain reset even though the overload current condition persists as long as the handle is held in circuit closed position. To this end, and as illustrated, the current responsive mechanism for operating the device automatically upon the occurrence of an abnormal current condition is biased from an operative position into an inoperative position by the same means which biases the movable contact member or switch arm into respective circuit open and circuit closed positions.

Another object of the invention is to improve generally upon the construction and operation of combined switches and circuit breakers.

With the above and other objects and features in view the invention will now be described with reference to the accompanying drawing in which:

Fig. 1 is a vertical cross-sectional view of a switch and circuit breaker embodying the present invention and showing the parts in circuit closed position;

Fig. 2 is a view similar to Fig. 1 but showing the parts in manual open circuit position;

Fig. 3 is a view similar to Fig. 1 but showing the parts in automatic open circuit position;

Fig. 4 is a view in cross section taken along the line 4—4 of Fig. 3; and

Fig. 5 is a view in cross section taken along the line 5—5 of Fig. 3.

The switch and circuit breaker illustrated in the drawing is of relatively small dimensions and is herein shown on an enlarged scale to approximately twice size. A small size breaker is desirable for many purposes, as in aircraft, for instance, but it is apparent that the circuit breaker may be made in other sizes, larger or smaller, if so desired.

The illustrated circuit breaker is arranged to be enclosed within a casing 10 which preferably is formed of one piece of molded plastic material such, for example, as Bakelite. The top of the casing 10 is provided with an opening 12 for receiving the manually operated handle 14 of the breaker. The bottom of the casing 10 is open so that the entire breaker assembly including the operating handle 14 may be inserted into the casing 10 in which it is held in position by pins 15 extending through the walls of the casing 10 and through the frame of the breaker assembly. Other holding means may, of course, be employed if so desired.

The breaker mechanism is supported on and between two sheets 16, 18 of suitable insulating material such, for example, as vulcanized fibre,

solid or laminated synthetic resin, or any other suitable rigid insulating material.

The circuit breaker includes a circuit terminal 20 having a bent lower end outside the casing provided with a threaded opening receiving a connecting screw for attaching a circuit conductor. The terminal 20 extends upwardly through a bottom plate 26 formed of suitable insulating material. The terminal 20 is wide enough to extend between the supporting sheets 16 and 18 and is provided at either side with ears 28 which extend through openings in the sheets 16, 18 and embedded in the openings and support the terminal 20 in fixed position and also rigidly connect the sheets. The upper end of the terminal 20 is provided with a suitable contact member 30 which cooperates in circuit closed position with a movable contact member 32 fixed to the lower end of a two part pivoted switch arm 34 which in turn is pivoted at its upper end to the supporting sheets 16, 18 by outwardly extending studs 36 fixed to or formed as a part of the upper ends of the legs of the switch arm 34.

The switch arm 34 is moved into and out of circuit open position by a pair of over-center ratchet springs 38 which are secured at their lower ends to a pin 40 extending through the lower ends of the legs of the switch arm 34. The upper ends of the springs 38 are secured to a pin 42 projecting from the opposite sides of the manually operated handle 14. The operating handle 14 is pivotally mounted on a pivoted support 44 which is normally maintained releasably in operative position by a latch 46 pivoted to a pin 48 extending through aligned openings in the sheets 16, 18. The pivoted support 44 is formed of two spaced parallel parts pivotally supported on a pin 50 and the handle 14 is pivotally supported between said parts on a pin 52 extending into aligned openings in said parts. The opposite ends of the springs tend to move toward each other. Thus, when the handle 14 is moved from the circuit closed position shown in Fig. 1 to the circuit open position shown in Fig. 2, the switch arm 34 will remain in circuit closed position until the line of force of the springs 38 passes beyond the dead center position or across the pivot 36 of the switch arm. The switch arm 34 will then move into circuit open position with a snap action independently of any further movement of the operating handle 14. The operating handle will move of its own accord into the open-circuit position illustrated in Fig. 2 when the line of action of the springs crosses the handle pivot 52. When it is desired to move the switch arm 34 into circuit closed position, the handle 14 is moved in the reverse direction until the line of force of the springs 38 passes beyond dead center position. The switch arm 34 will then move into circuit closed position and into electrical engagement with the stationary contact 30 and the handle will stay in circuit closed position under action of the springs. It is apparent, therefore, that the breaker is operable manually to open and close the circuit with a snap action which prevents excessive or long continued arcing between the movable and stationary contact members.

The supporting member 44 is arranged to move about its pivot 50 in a counter-clockwise direction into an inoperative position upon the occurrence of a relatively long continued predetermined overload current. To this end, a bimetal strip 54, comprised of two metals of dissimilar coefficients of expansion secured together back to back, is fixed at its lower end to a terminal

56 having outwardly projecting ears 58 extending through openings and fixed in the sheets 16, 18 to anchor the terminal 56 in position. The lower end of the terminal 56 is bent horizontally and is provided with a threaded opening for receiving a connecting screw 60 for a circuit conductor. The upper end of the terminal 56 is provided with a threaded hole for receiving an adjusting screw 62. The adjusting screw 62 extends through the opening and bears against the bimetal strip 54 to adjustably position the upper free end of the strip 54 relatively to the lower end 64 of the latch 46, which, when sufficiently thermally warped, is arranged to engage and move away from holding relation with the support 44, to permit the release of said support. By positioning the free end of the bimetal strip 54 further away from the end of the latch 46, the free end thereof will have to warp farther 20 before it will move the end of the latch sufficiently to trip the latch 46 to free the support 44 and to permit it to move to inoperative position.

When the support 44 is freed from the latch 23 46, the springs 38 become effective to move the support 44 into the position shown in Fig. 3 since the line of action of the springs lies to the left of the pivot 50 for the support. The handle 14 which, as shown in Fig. 1, bears against the pivot 30 pin 50 will be swung in a counter-clockwise direction about the pivot pin 50 as a fulcrum, the handle also camming on the pin by reason of the inclined cam face 51 of the handle. When the spring supporting pin 42 of the handle crosses 35 the center line passing through the spring supporting pin 40 of the switch arm and the pivot 36 of the switch arm the switch arm will move to open-circuit position and will carry the line of action of the spring across the pivot pin 52 40 of the handle thereby moving the handle to open-circuit position. Thus, the switch arm 34 will be moved in a counter-clockwise direction from the position shown in Fig. 1 to the position shown 45 in Fig. 3. The extent of opening or clockwise movement of the switch arm 34 is limited by a stop 66 fixed in position between the sheets 16, 18.

When it is desired to reclose the breaker after automatic opening thereof, it is necessary only to move the handle from the position shown in Fig. 3 toward the right. The handle 14 will then engage the pivot pin 50 about which the handle 50 14 and the support 44 will fulcrum and cam to move the support 44 into the position shown in Fig. 1. During this resetting movement, the line 55 of action of the springs 38 will pass across and to the right of the pivot 36 for the switch arm 34 which then, of course, will move into circuit closed position with a snap action. If the bimetal strip 54 has returned to its normal position, as 60 shown in Fig. 1, the latch 46 will engage the end of the support 44 and will maintain the parts in circuit closed position. If, however, the latch 46 has not returned to the position shown in Fig. 1 the circuit will remain closed as long as 65 the operator holds the operating handle 14 in the position shown in Fig. 1.

I claim:

1. In a combined switch and circuit breaker, the combination of a switch arm movable between circuit open and circuit closed positions, a fixed pivot for said movable switch arm, a pivoted operating handle movable between said circuit open and closed positions, a supporting arm on which said operating handle is pivotally secured, an over-center spring connecting said operating

handle and said switch arm, a pivot for said supporting arm displaced relatively to said pivots for the switch arm and for the operating handle to locate the pivots for the operating handle and the switch arm on one side and the pivot for the supporting arm on the opposite side of the line of action of said over-center spring when the parts are in circuit closed position, and current responsive means for maintaining said supporting arm in operative position and arranged upon the occurrence of a predetermined abnormal current condition to release said supporting arm to permit movement thereof and to move the pivot for the operating handle to the other side of the line of force of the over-center spring to cause said spring to move said operating handle into circuit open position and subsequently to move said contact carrying arm into circuit open position with over-center spring snap action.

2. In a combined switch and circuit breaker, a contact carrying arm movable between circuit open and circuit closed positions, a fixed pivot for said contact carrying arm, a pivoted operating handle, a displaceable support upon which said operating handle is pivoted, a fixed pivot for said support, over-center spring means connecting said operating handle and said contact carrying arm, and current responsive means normally maintaining said support in operative position but releasable upon the occurrence of a predetermined overload current to move into an inoperative position and causing the operating handle to fulcrum about the pivot of said support to cause the operating handle to rotate in a circuit opening direction, thereby causing the over-center spring means to be moved beyond dead center position to cause movement of the contact carrying arm from circuit closed to circuit open position with over-center spring snap action.

3. An electric switch comprising a pivoted switch member, a pivoted operating member, an over-center spring operative to move said switch member with snap action from a position corresponding to circuit closed position to a position corresponding to circuit open position in response to corresponding movements of said operating member and to bias said switch member to remain in whichever of said positions it is located, and current-responsive means to permit shifting of the pivot of said pivoted operating member to effect automatic movement of said switch member from circuit closed to circuit open position and corresponding movement of said operating member, said operating member having means responsive to manual pressure thereon in a circuit closing direction preventing the shifting of the pivot thereof, and means responsive to movement of said operating member in a circuit closing direction operative to restore the shifted pivot thereof.

4. An electric switch comprising a pivoted switch member, a pivoted operating member, an over-center spring operative to move said switch member with snap action from a position corresponding to circuit closed position to a position corresponding to circuit open position in response to corresponding movements of said operating member and to bias said switch member to remain in whichever of said positions it is located, and current-responsive means to permit shifting of the pivot of said pivoted operating member to effect automatic movement of said switch member from circuit closed to circuit open posi-

tion and corresponding movement of said operating member, said operating member having means resistive to manual pressure thereon in a circuit closing direction preventing the shifting of the pivot thereof.

5. An electric switch comprising a pivoted contact carrying member, a pivoted trip member, a manually operable member pivoted on said trip member, electro-responsive means releasably holding the trip member in operative position, and an over-center spring operative following release of the trip member by the electro-responsive means first to rotate the trip member about its pivot, then to rotate the manually operative means about its pivot, and ultimately to rotate the contact carrying member about its pivot from circuit closed to circuit open position with over-center spring snap action.

6. In a combined switch and circuit breaker, a contact carrier movable between circuit open and circuit closed positions, a manually operable member mounted on a movable pivot, means normally and releasably supporting said pivot, and an over-center spring bridging said pivot and having its ends connected respectively to said contact carrier and said manually operable member and biasing said pivot away from its supported position and in direction across the line of action of the spring, said means being operative under normal circuit conditions to release said pivot, and said spring then being operative to effect relative movement of the line of action of the spring and said pivot across each other thereby to effect snap movement of the contact carrier from its circuit closed position to its circuit open position.

7. In a combined switch and circuit breaker, a contact carrier movable between circuit open and circuit closed positions, a manually operable member mounted on a movable pivot, a swinging latch member on which said manually operable member is pivotally mounted, means normally maintaining said latch member in latched position and operative in response to abnormal circuit conditions to release the latch member, and an over-center spring bridging the latch member and having its ends connected respectively to said contact carrier and said manually operable member and biasing said latch member away from its latched position in direction across the line of action of the spring, said spring, upon release of the said latch member, being operative to effect relative movement of the line of action of the spring and said movable pivot of the manually operable member across each other thereby to effect movement of the contact carrier from its circuit closed position to its circuit open position with over-center spring snap action.

8. In a combined switch and circuit breaker, three pivoted members of which one is a contact-carrying member, another is a trip member, and the third is a manually operable member whose pivot is on the trip member, means normally maintaining the trip member in operative position and responsive to abnormal circuit conditions to release the trip member, and an over-center spring bridging all of the pivots of said pivoted members and having its ends connected respectively to said contact-carrying member and said manually operable member and biasing said trip member from its said operative position in direction across the line of action of the spring, said spring, upon release of the trip member, being operative to effect relative movement of the line of action of the spring and said pivot of the man-

ually operable member across each other thereby to effect movement of the contact-carrying member from a circuit closed position to a circuit open position with over-center spring snap action.

9. In a combined switch and circuit breaker, three pivoted members of which one is a contact-carrying member having a fixed pivot, another is a trip member, and the third is a manually operable member having a movable pivot on the said trip member, means normally maintaining the trip member in operative position and responsive to abnormal circuit conditions to release the trip member, an over-center spring bridging all of the pivots of said pivoted members and having its ends connected respectively to said contact-carrying member and said manually operable member and biasing said trip member from its said operative position in direction across the line of action of the spring, said spring, upon release of the trip member, being operative to move the said movable pivot of the manually operable member in direction across the line of action of the spring, and there being means on said manually operable member for coacting with said

fixed pivot of the contact-carrying member, to shift the line of action of the spring in direction across said movable pivot.

10. In a combined switch and circuit breaker, a manually operable member, a contact-carrying member mounted on a fixed pivot, means releasably supporting the manually operable member in operative position on a movable pivot, and an over-center spring maintaining the manually operable member and the contact-carrying member in their circuit closed positions with the line of action of the spring on one side of both the said fixed pivot and the said movable pivot, said means being operative in response to abnormal circuit conditions to release said movable pivot of the manually operable member thereby to permit movement of said movable pivot by the spring across the line of action of the spring, and said spring then being operative to shift its line of action to the other side of said fixed pivot to effect over-center spring snap action of the contact-carrying member from its said circuit closed position.

CARL A. CHRISTOFFERSON.
